US0D1113040S

(12) **United States Design Patent** (10) Patent No.: **US D1,113,040 S**
(45) Date of Patent: ** Feb. 10, 2026

(54) **PAINT CONTAINER LINER**

(71) Applicant: **Bercom International, LLC**,
Chanhassen, MN (US)

(72) Inventors: **Mark W. Bergman**, Minnetonka, MN
(US); **Jeffrey T. Given**, St. Paul, MN
(US); **Matthew V. Leyden**, St. Paul,
MN (US); **Jeffrey B. Waffensmith**,
North Oaks, MN (US)

(73) Assignee: **Bercom International, LLC**,
Chanhassen, MN (US)

(**) Term: **15 Years**

(21) Appl. No.: **29/914,398**

(22) Filed: **Oct. 17, 2023**

(57) **CLAIM**

The ornamental design for a paint container liner as shown and described.

DESCRIPTION

FIG. 1 is a perspective view of a paint container liner;
FIG. 2 is a left side view of the paint container liner of FIG. 1;
FIG. 3 is a right side view of the paint container liner of FIG. 1;
FIG. 4 is a back view of the paint container liner of FIG. 1;
FIG. 5 is a front view of the paint container liner of FIG. 1;
FIG. 6 is a top view of the paint container liner of FIG. 1;
and,
FIG. 7 is a bottom view of the paint container liner of FIG. 1.
The broken lines illustrate portions of the paint container liner that form no part of the claimed design.
